UNITED STATES PATENT OFFICE

JOHN H. UHRIG, OF BEVERLY, NEW JERSEY, ASSIGNOR TO UNITED STATES CAST IRON PIPE & FOUNDRY COMPANY, OF BURLINGTON, NEW JERSEY, A CORPORATION OF NEW JERSEY

CENTRIFUGAL PIPE-CASTING MACHINE

Application filed May 18, 1928. Serial No. 278,707.

My invention relates to pipe casting machines of the well known de Lavaud type in which relatively movable water jacketed molds and metal delivering runners are employed so that the runner at the beginning of the pipe casting operation extends practically throughout the length of the mold and is gradually withdrawn therefrom during the pouring of the metal so that the metal is delivered to the surface of the mold in what might be called a spiral coil. In machines of this kind it is found necessary that the mold and runner should be inclined to a horizontal plane to facilitate the delivery of metal through the runner with sufficient speed and, depending on the fluidity of the metal delivered to the mold, there is more or less tendency of the molten metal to flow longitudinally in the mold before it sets and thereby to bring about the formation of pipe with walls of uneven thickness. I have devised and improved method of casting pipes in machines of this kind in accordance with which I diminish the inclination of the mold during the pouring of the pipe in such a way as to counteract the tendency to an objectionable longitudinal flow of the metal in the mold before it sets, my improved method preferably also involving the pouring of the metal into the runner at a point bearing a fixed relation to the end of the mold through which the runner passes so that as the runner is withdrawn from the mold the metal poured into it has a progressively shorter path of travel before reaching the mold. My improved method forms the subject matter of a pending application filed May 18, 1928, Serial No. 278,708, my present invention relating to improvements in the construction of the casting machinery which I have devised to facilitate the practice of my improved method. These mechanical means will be best understood as described in connection with the drawings which illustrate a machine embodying my invention and in which—

Figure 1 is an elevation of my improved casting machine.

Figures 2, 3, and 4, illustrate the same machine on an enlarged scale, each of said figures illustrating a section of the machine and

Figures 2 and 3 showing certain details of construction in section.

Figure 5 is a cross sectional elevation on the line 5—5 of Fig. 3, and

Figure 6 is a cross sectional elevation on the line 6—6 of Fig. 3.

A, A¹ and A² are supporting tracks for the frame of the machine. These tracks, as illustrated, are formed on arcs of concentric circles, the tracks, as distinguished from the supports, being indicated at a, a¹, and a². B is a frame provided with supporting wheels B¹, B² and B³ which rest on the concentric tracks. The frame supports longitudinal tracks indicated at B⁴ and have stops as indicated at B⁵ and B⁶ at the ends of the tracks. B⁷ indicates a bracket secured to the under side of the frame B to which is coupled a connecting rod B⁸ actuated by the piston rod C¹ of a cylinder and piston indicated at C, constituting a power motor by which the frame B can be longitudinally shifted at the will of the operator. D is a frame or bracket secured to the left hand end of the frame B which supports the end D¹ of a runner D² from the end D³ of which the molten metal is delivered into the mold. E is the ordinary water box carriage longitudinally movable on the frame B and supported on the tracks B⁴ by means of its wheels indicated at E¹. E² are rollers journalled in the water box serving as supports for the mold F. E³ is a lug secured to the bottom of the water box carriage. F is the rotary mold extending through the water box and rotated by a motor G to the spindle G¹ of which is attached a gear G² meshing with the gear G³ which in turn engages a gear wheel on the driving ring F¹ attached to the bell end of the mold, as best shown in Fig. 3. H is a rack bar pivoted to the lug E³, as shown in Fig. 3, and supported and guided for longitudinal movement in the frame B by means of the rollers indicated at H¹, best shown in Figures 3 and 5, and the roller H². Motion is given to the rack bar and through it to the frame by the mechanism best shown in Figure 5 consisting of a gear wheel H³ turning on the spindle H⁴ and geared with the gear wheel H⁵ mounted on the spindle H⁶ which in turn is rotated by

gear wheel H^7 geared with gear wheel H^8 , the shaft H^9 of which is coupled to a sprocket wheel H^{10} , operated by a sprocket chain through sprocket wheel H^{11} on a shaft H^{12} which is coupled to a motor indicated at H^{13} . The employment of a guided rack bar as a means for reciprocating the mold carriage is a minor feature of novelty in my construction.

10 I indicates a trough which I preferably use, as shown in Figure 2, at the end of the mold into which the runner enters as a convenient device to catch any metal which may run out of the end of the runner after it is withdrawn from the mold.

15 J is a carriage supported on the tracks B^4 of the frame B by wheels indicated at J^1 , the carriage supporting a runner J^2 which registers with the open top of the runner D^2 and supporting also a tilting ladle indicated at J^3 which is pivoted to the carriage at its pouring lip J^4 and is tilted by means of a lever J^5 actuated, as shown, by a threaded rod J^6 engaged with a nut wheel J^7 which is actuated through intermediate gearing, not shown, attached to a shaft J^8 which in turn is coupled by link J^{10} with a motor indicated at J^{11} .

20 K is a stop secured to the track A and serving as a limit stop for the longitudinal motion of the frame B .

25 L, L^1 indicate an electro-magnet and armature secured to the carriage J and carriage E by which they are coupled during such portion of the casting operation as may be desired.

30 The operation of my machine will be readily followed. At the beginning of the pouring operation the mold carriage occupies the position shown in Figure 1, in which position the runner D^2 extends practically throughout its length nearly to the bell end of the mold. The carriage J is coupled to the mold, the mold is rotated, the carriage E with its connected mold is moved toward the right by the rack bar and connecting mechanism described and the ladle J^3 is gradually tilted to pour the metal into the runner and through it into the mold. At the beginning of the 35 operation the frame B is in its most extremely tilted position that is in the position in which its end supporting the runner and ladle is elevated and its opposite end depressed so as to facilitate the flow of metal through the runner into the mold. As the pouring progresses the operator, through the piston C , shifts the frame B toward the left so that, moving on the inclined tracks which support it, it is lifted to a progressively less 40 angle to the horizontal, the points at which the tilt is varied and the degree of tilt being within the control of the operator. As the mold recedes from the relatively stationary runner the carriage J moves with the mold so that the metal poured from the ladle J^3 enters

the runner at a point bearing a fixed relation to the end of the mold and thus at progressively closer points to the delivery end of the runner, thus cutting down the frictional resistance to the flow of metal from the runner and making it possible for the diminishing inclination of the runner to still deliver the proper amount of metal to the mold.

70 It will, of course, be obvious that the ladle can be uncoupled from the mold during the operation of such portions of the machine as should make it desirable that the mold carriage should move without an accompanying movement of the ladle carriage.

75 Having now described my invention, what I claim as new and desire to secure by Letters Patent, is:

1. In a centrifugal pipe casting machine of the type in which the molten metal is progressively delivered to the rotating mold through a relatively retractable runner, the improvement which consists in supporting the mold and relatively retractable runner on an angularly adjustable frame and providing in combination therewith power actuated mechanism for varying the angle of inclination of the frame during the pouring of the mold.

80 2. In a pipe casting machine having the features of claim 1, means for tilting the supporting frame consisting of inclined supports for the frame and power means for shifting the frame longitudinally on said support.

85 3. In a pipe casting machine having the features of claim 1, means for tilting the supporting frame consisting of a series of supports for the frame curving in concentric arcs and power means for shifting the frame longitudinally on said concentric supports.

90 4. A pipe casting machine having the features of claim 1, in combination with a pouring ladle and ladle supporting means adapted to hold the ladle in fixed position with respect to the mold during the pouring of the mold.

95 5. A centrifugal pipe casting machine comprising in combination a frame angularly adjustable in a vertical plane, a carriage longitudinally movable on said frame, a rotary mold, supported on said carriage, a runner supported on the frame adapted to deliver metal to the mold during the longitudinal movement of said mold and power actuated means adapted to vary the angular inclination of the frame during the pouring of the mold.

100 6. A pipe casting machine having the constructive features of claim 5 and having in combination therewith a pouring ladle and a pouring ladle support longitudinally movable with respect to the frame and means for coupling the ladle support and the mold carriage during the pouring of the mold so that

the ladle will be held during the pouring in fixed relation to the mold.

7. A pipe casting machine having the constructive features of claim 5 and having in combination therewith a pouring ladle and a pouring ladle support supported on and longitudinally movable with respect to the frame and means for coupling the ladle support and the mold carriage during the pouring of the mold so that the ladle will be held during the pouring in fixed relation to the mold.

8. A pipe casting machine having the features of claim 5 in which the frame is supported on inclined supports and is angularly adjusted by power actuated means acting to shift it longitudinally on said supports.

9. A pipe casting machine having the features of claim 5 in which the frame is supported on a series of arc shaped concentric tracks and is angularly adjusted by power actuated means acting to shift it longitudinally on said concentric tracks.

10. A pipe casting machine having the features of claim 5, in combination with means for reciprocating the mold carriage comprising a rack bar supported for longitudinal movement on the frame and attached to the carriage and power means for reciprocating the rack bar supported also on the frame.
